ANNA GERTRUDE KAHN, OF CENTERVILLE, MARYLAND.

COAL-CAR COVER.

1,258,576.

Specification of Letters Patent. Patented Mar. 5, 1918.

Application filed August 27, 1917. Serial No. 188,412.

To all whom it may concern:

Be it known that I, ANNA GERTRUDE KAHN, a citizen of the United States, residing at Centerville, in the county of Queen Annes and State of Maryland, have invented certain new and useful Improvements in Coal-Car Covers, of which the following is a specification.

This invention relates to an improved coal car cover and the principal object of the invention is to provide a cover so constructed that the longitudinal side sections thereof may be swung out of the way when loading or unloading and may then be swung to extend over the load and retain the load in place thus preventing waste as the train passes over rough places in the road and jolts the cars.

Another object of the invention is to so construct the cover that the end portions will be solid and not only add strength in resisting longitudinal movement of the load but further provides strong supports for the end portions of the movable side sections.

Another object of the invention is to so construct the cover that it can be easily connected with a coal car of a conventional construction and thus permitted to be connected with cars already in use.

This invention is illustrated in the accompanying drawings, wherein:—

Figure 1 is a view showing the cover and a portion of a coal car in side elevation,

Fig. 2 is a top plan view of the improved cover, and,

Fig. 3 is a transverse sectional view taken along the line 3—3 of Fig. 1.

The cover is connected with the coal car the upper portion of which is shown in Fig. 1 and in Fig. 3 and is provided at each end with a solid wall 11 extending beneath the upper edge of the coal car. The side sections indicated in general by the numeral 12 are formed of longitudinally extending rods having their end portions carried by strips 13 which together with the longitudinally extending strips 14 constitute the frame for the side sections. These side sections are hingedly mounted by bearings 15 extending from the side strips 16 and it will

thus be seen that when it is desired to load or unload the car, the side sections may be swung outwardly thus permitting ready access to the interior of the car. Eyes 17 extend from the strips 14 and meet when the cover is in a closed position thus permitting a lock 18 to be put in place to hold the cover closed. When the cover is closed, there will be provided means for holding the coal in place and not only preventing the coal from being spilled from the car when the train is moving but further so constructed that the removal of the coal from the car by unauthorized persons will be prevented. There has further been provided a cover so constructed that longitudinal moving of the coal caused by coupling of cars will not be liable to tear the cover loose.

I have thus provided a very serviceable car cover so constructed that the coal will be securely held in place and further so constructed that the cover may be readily connected with a car already in use.

What is claimed is:—

In a device of the character described a receptacle provided with side and end walls and having an open upper end, and a cover for said receptacle comprising solid end walls connected with the end walls of the receptacle and having curved sides, side strips leading from one end wall of the cover to the other along the side walls of the receptacle, side sections for the cover having end strips resting upon the end walls of the cover, and conforming to the contour thereof, longitudinally extending rods carried by the end strips, eyes carried by the side strips and engaging the lower rod to hingedly mount the side sections, longitudinally extending strips extending between the end strips at the free sides of said sections, and means releasably connecting the side strips of the side sections to hold the side sections in a closed position.

In testimony whereof I affix my signature in presence of two witnesses,

ANNA GERTRUDE KAHN
